POWER MECHANISM.

Application filed January 16, 1926. Serial No. 81,719.

This invention relates to power mechanism suitable for use in connection with a typewriter, or other machine, in which a series of type-bars or the like are to be actuated selectively.

In certain power mechanisms for the purpose in question, it has heretofore been proposed to use a constantly rotary power-roller, driven by an electric motor or other suitable source of power, and to connect with each type-bar, or other device which is to be actuated, an actuating unit or assembly including means which may be thrown into engagement with the power-roller to derive movement therefrom. The present invention relates to mechanism of the general character just described, and the novelty of the invention resides particularly in the means which engage and are directly actuated by the roller.

In accordance with the present invention, the roller is caused to move a movable member or "actuator" mounted adjacent the roller, by means of an interponent which is formed and adapted to roll freely between the surface of the power-roller and an opposed face or surface on the actuator, this interponent being thrown into operative engagement with these parts by suitable selective means, such as manually operable keys.

In the accompanying drawings, Fig. 1 is a side-elevation, partly in section, showing power mechanism embodying the present invention, as applied to a typewriter. Fig. 2 is a detail from Fig. 1, but on a larger scale, showing particularly the power mechanism with the parts in the position assumed at the end of the operative movement. Fig. 3 is a rear-elevation of the parts shown in Fig. 2.

The invention is illustrated as embodied in a typewriter having the usual type-bars 5, mounted on a pivot 6 and actuated by bell-crank levers 7 which are pivoted at 8. Each bell-crank lever is connected, in a well known manner, with a corresponding type-bar, by means of a pin 9; and a spring 10, attached to the lever, tends to return it to the normal position shown in Fig. 1, with its upper arm resting against a stop-bar 11.

The power-roller is shown as a hollow member, which is made preferably of hardened steel, and is longitudinally serrated on its outer surface. The actuators through which the several type-bars are moved have

the form of a series of bell-crank levers 13, mounted on a pivot-rod 14 which is supported by a transverse member 15 on the frame of the machine. The upper horizontal arm of each actuator 13 is connected, by a link 16, with the corresponding lever 7.

The interponent characteristic of the present invention is shown as having the form of a disc 17, which is preferably made of hardened steel, and is serrated at its periphery. This disc lies loosely between the forward ends of two parallel arms 18, which are interconnected and are pivoted to the actuator by means of a transverse pin 19. The forward ends of the arms are slotted to receive trunnions 20, projecting axially from the disc 17. The disc is of the same thickness as the actuator 13, and the latter has a working face 21, which is preferably serrated, and is opposed to the power-roller. At its lower end the actuator terminates in a hook-like extremity 22, which serves normally as a seat to support the disc, and in this normal position of the parts the disc is out of engagement with the power-roller.

The unit of the power mechanism just described is controlled by a key 23, forming part of the usual keyboard of the typewriter. This key moves a key-lever 24, which is pivoted at 25, the key being held normally in raised position by a spring 26. At its rear end the key-lever carries a trip 27, of which the upper end lies normally beneath shoulders 28 on the arms 18, as shown in Fig. 1. When the key is depressed the trip engages the shoulders and swings the arms upwardly, thereby bringing the interponent 17 into engagement with the power-roller. Since this roller turns in a clockwise direction, it at once rolls the interponent upwardly along the face 21, and since this face is at an angle with the surface of the roller, the result is to cause the actuator 13 to swing about its pivot 14 into the position shown in Fig. 2, thus swinging the type-bar up into operative position.

In order that the interponent may be released at the end of this operation, to permit its return to normal position, the parts are so proportioned that the type-bar has not quite reached the platen at the time when the interponent reaches the highest point on the face 21 of the actuator. Accordingly, the last part of the movement of the type-bar occurs in consequence of the momentum

which it has already acquired, and in completing its movement the type-bar acts, through the intervening mechanism, to swing the actuator slightly beyond the position shown in Fig. 2, thus releasing the interponent from pressure against the power-roller. The interponent is then immediately returned to its original position, this return occurring before the actuator has time to 10 swing back sufficiently to cause renewed engagement with the power-roller. This return of the interponent is caused in part, when the apparatus is arranged as illustrated, by the action of gravity, but to render 15 it more rapid and certain a spring 29 is also used, this spring having the form of a blade mounted on the frame-member 15. The lower end of the spring cooperates with upwardly projecting lugs 30 on the arms 18. 20 Normally these lugs are in a position in front of and out of engagement with the spring 29, so that no resistance is opposed to the movement, by the controlling key, of the arms and the interponent but the 25 rearward swinging movement of the actuator causes the lugs to engage the spring, so that the spring acts to swing the arms downwardly as soon as the interponent is released from its rolling engagement with the power-roller. 30 The complete cycle of movement of the interponent and the actuator takes place so rapidly that the key is usually still in depressed position until after the mechanism has returned to normal position. In order 35 that this may not cause interference with the return of the mechanism, the trip 27 is mounted on a pivot 31 on the key-lever, and is held in its normal position by a light spring 32 with the lower end of the trip 40 resting against a stop-lug 33. Upon the return of the actuator and the arms 18 to normal position, the upper end of the trip rests against the forward surfaces of the shoulders 28, and is by them swung forwardly. Upon the subsequent release and

return of the key-lever, however, the spring 32 swings the trip back to its normal position shown in Fig. 1, ready for another operation.

It will be understood that as many of the power-units shown and described may be arranged side-by-side along the power-roller as may be necessary to actuate the several type-bars, or other parts of the machine, each such unit being controlled separately by a key or other convenient means. The mechanism of the present invention has the advantage, among others that the connection between the power-roller and the actuator 13 is the result of a purely rolling movement of the interponent, so that the power is transmitted positively and at the same time with a minimum of friction and wear. For the same reason, little or no lubrication of the mechanism is necessary, and each unit, in spite of its positive action, may be designed to occupy a narrow space, since it is not necessary to provide bearing surfaces of any substantial width.

The invention claimed is:

1. Power mechanism, for a typewriter or the like, comprising a constantly rotary power-roller, an actuator movably mounted adjacent the roller and having a working face opposed thereto, an interponent adapted to have rolling engagement with said face and said roller, and means for moving said interponent into such engagement to cause movement of the actuator.

2. Power mechanism, for a typewriter or the like, comprising: a constantly rotary power roller, a lever pivoted adjacent said roller and having a cam surface opposed thereto, a peripherally serrated disc adapted to roll between said cam surface and said power roller, two arms pivoted to said lever and said disc, and key-controlled means for swinging said arms to move the disc into operative engagement with the power-roller.
